UNITED STATES PATENT OFFICE.

ELWYN Z. COLB, OF PHILADELPHIA, PENNSYLVANIA.

LOCK NUT.

Application filed July 22, 1924. Serial No. 727,461.

My invention relates to a new and useful improvement in nut locks and has for its object to improve upon the principle and construction shown in my former applications for patents under Serial No. 688,023, filed January 23rd, 1924 and Serial No. 689,840, filed February 1st, 1924, whereby a device of this description may be produced which will be especially adapted for use in various classes of work and which will render the locking and unlocking of the nut more simple and effective than has heretofore been the case and which will cheapen its construction and enhance its value as a standard article of commerce.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1, is a plan view of one form of my present invention.

Fig. 2, is a side view of Fig. 1, the retaining cap being in section.

Fig. 3, is an end view of Fig. 2, before the lock nut has been applied to the bolt.

Fig. 4, is a side view of Fig. 3.

Fig. 5, is a top plan view of the nut, a portion of the turret being broken away to show the contour of the undercut.

Fig. 6, is a side view of Fig. 5.

Fig. 7, is a view similar to Fig. 5 showing a slightly modified form of the contour of the undercut.

Fig. 8, is a side view of Fig. 7.

Fig. 9, is a bottom plan view of the retaining cap showing the preferred form of fasteners for securing the retaining cap in place.

Fig. 10, is a side view of Fig. 9.

Fig. 11, is a plan view of the split locking washer for holding the nut against retrograde movement.

Fig. 12, is an edge view of Fig. 11.

Fig. 13, is a plan view of a further modification of my present invention.

Fig. 14, is a side elevation of Fig. 13, the retaining cap being in section to clearly show the engagement of the locking means with the undercut section of the turret.

Fig. 15, is a plan view of the nut.

Fig. 16, is a side view of Fig. 15.

Fig. 17, is a bottom plan view of the retaining cap utilized in this modified construction.

Fig. 18, is a view similar to Fig. 17 but showing the cap sprung out of true so as to increase the distance between the retaining lugs thereof in order that the latter may be passed over the turret of the nut for engagement with the undercut portion thereof.

In carrying out my invention as embodied in Figs. 1 to 8 inclusive, 1 represents a nut having a hub 2 formed therewith and this hub has the teeth or serrations 3 formed upon the face thereof, said teeth preferably being in the form of ratchet teeth and this nut is adapted to run upon the bolt 4 having the spline grooves 5 therein, it being understood that one or more of such splines may be utilized as occasion may require.

The turret 2 has formed upon diametrically opposite sides thereof the undercut depression 6 which in Fig. 5 is of ratchet shape, whereas in Fig. 6, 7 and 8, these depressions are simply flattened portions for the purpose hereinafter set forth.

8 represents the retaining cap which is adapted to snugly fit over the turret 2 and this cap has cut therefrom the latch tongues 9 which are bent inward as clearly shown in Fig. 9 so that when this cap is passed over the rounded edge 10 of the turret the latch tongues 9 will be forced outward so that the cap may be pushed into place entirely surrounding the turret permitting the latch tongues to snap under the shoulders 11 of the undercut portions 6 thereby retaining the cap against accidental displacement or withdrawal, it being understood that the spring action of the tongues will hug the vertical surfaces of the depressed portions with sufficient force to prevent the cap from being accidentally turned on its axis, but to permit said cap to be turned upon its axis when sufficient force is applied to the cap for that purpose.

12 represents a split spring lock washer which has formed upon its inner periphery the lugs 13 the latter being adapted to slide in the grooves 5 of the bolt, the object of which is to prevent the turning of the lock washer independent of the bolt but to permit its travel thereon lengthwise of the bolt. This lock washer is placed over the bolt so

that its downturned end 14 will engage with the teeth 3 upon the face of the turret after the manner of a ratchet when the cap 8 is snapped into place as before described, thus 5 confining the washer in position and putting sufficient pressure upon the same to keep the ratchet tooth 14 thereon in constant engagement with the teeth 3.

From this description it will be seen that 10 as the nut is set up upon the bolt the teeth 3 will travel under the ratchet tooth 14 and whenever the nut has been screwed home this engagement will prevent any retrograde movement of the nut, thus securely locking 15 it against displacement either accidentally or by vibration.

When it is desired to unlock the nut it is only necessary to turn the retaining cap 20 upon its axis until the latch tongues 9 ride from beneath the shoulders 11 after which the cap may be readily withdrawn from the 25 turret giving access to the locking washer in order that it may be disengaged from the teeth 3 and permit the backing off of the nut.

The modification shown in Figs. 13 to 18 30 inclusive, provides for the retaining cap 21 having latch lugs 22 formed upon its inner surface by either pressing portions of the metal cap inward or by partially cutting portions of the metal from the cap and pressing the same inward as clearly shown in Fig. 14.

These latch lugs will be forced apart when 35 the cap is forced over the turret on account of there being sufficient spring in the cap to permit the elongation thereof upon the diameter on which the lugs are formed by the distortion of the cap from a true circle and to an oval, as clearly shown in Fig. 18, and 40 when the upper edge of these lugs pass under the shoulders 11 of the depressions 6 the spring of said cap will cause these lugs to snap beneath their shoulders, thus holding the cap against accidental displacement but 45 permitting its removal by the turning thereof upon its axis until the lugs ride up upon the round portion of the turret when the cap is free to be withdrawn.

While there are various other modifications that might be here shown and described many of which will be obvious to one skilled in the art to which this invention appertains, I have deemed it unnecessary to ex-

tend the showing and description of my present invention beyond that herein embodied, but I do not wish to limit this invention to the modifications here shown nor to the details of construction as herein shown as these may be varied within the limits of the appended claims without departing from the spirit of my invention.

Having thus fully described my invention, what I claim as new and useful is:—

1. A lock nut comprising a nut with a 65 turret formed thereon and teeth formed on the face of the turret, a bolt on which said nut is threaded, said bolt having spline grooves lengthwise thereof, a split spring lock-washer one end of which is adapted to engage said teeth as a ratchet, lugs formed with the washer and adapted to run in the spline grooves, undercut depressions on the sides of the turret, a cap adapted to fit over the turret, and means for detachably holding the cap in place on the turret whereby the split spring lock-washer is held in operative position and providing for the removal of the cap for the unlocking of the locking means.

2. In a device of the character described, 70 a nut having a turret formed thereon, teeth formed upon the face of the turret, a bolt upon which the nut and turret are threaded, said bolt having lengthwise grooves formed therein, a lock-washer for engagement with said teeth, said washer having lugs fitted to run in said grooves, a cap, inwardly projecting lugs on the cap, and an undercut depression on the sides of the 75 turret with which the last named lugs are 80 adapted to engage by the distortion of the cap.

3. A nut lock comprising the combination 85 of a longitudinally grooved bolt, a nut for threaded engagement with the bolt, ratchet teeth on said nut, a lock washer having means registering with the groove in the bolt and other means coacting with the ratchet teeth and a cap detachably connected with the nut and coacting with the lock 90 washer so as to retain the latter in working position relative to the nut as said nut is moved along the bolt.

In testimony whereof, I have hereunto affixed my signature.

ELWYN Z. COLE.
